UNITED STATES PATENT OFFICE.

JULIUS F. JAQUET, OF MILWAUKEE, WISCONSIN, AND WILLIAM McAUSLAN,
OF BROOKLYN, NEW YORK.

SIDEWALK.

SPECIFICATION forming part of Letters Patent No. 446,752, dated February 17, 1891.

Application filed November 8, 1890. Serial No. 370,782. (No model.)

To all whom it may concern:

Be it known that we, JULIUS F. JAQUET, of Milwaukee, in the county of Milwaukee and State of Wisconsin, and WILLIAM McAUSLAN, 5 of Brooklyn, in the county of Kings and State of New York, have invented a new and Improved Sidewalk, of which the following is a full, clear, and exact description.

This invention relates to improvements in 10 sidewalks for streets or other thoroughfares, and has for its objects to produce a sidewalk or pavement for pedestrian travel which will be of a simple and durable construction and which may be quickly put in place or be 15 speedily detached for repair, utilizing either wood or terra-cotta with metal as a material for its manufacture.

To these ends our invention consists in certain features of construction and combinations of parts, as is hereinafter described and 20 claimed.

Reference is to be made to the accompanying drawings, forming a part of this specification, in which similar letters of reference indicate 25 corresponding parts in all the figures.

Figure 1 is a plan view of a supporting device for the tread-pieces of the sidewalk, which tread-pieces are shown broken and in dotted lines. Fig. 2 is a cross-section of the 30 tread-pieces of a sidewalk and their supports, the latter being cut on the line 2-2 in Fig. 1. Fig. 3 is a side elevation of one of the bracket-stands used to support the treads of the sidewalk. Fig. 4 is an end view of the tread- 35 support shown in Fig. 1, viewed in the direction of the arrow 4 in said figure. Fig. 5 is a plan view of reduced size, showing the tread-pieces of the sidewalk in secured position on their supports. Fig. 6 is a side view 40 in section of two broken sill-plates joined by a splice-bar.

Briefly considered, the improved sidewalk is composed of bracket-stands, which are arranged in series on elongated metal sills, 45 whereon wooden planks or terra-cotta slabs are secured by their interlocked engagement with projections on the upper portions of the bracket-stands, the several bracket-stands of each series on a sill being suitably clamped 50 together thereon. By provision of an indefi-

nite number of such treads, sills, and stands a continuous, durable, and level wearing-surface is afforded of any desired width and length, as will appear in the following detailed description. The bracket-stands A are 55 alike in form. Hence a description of one will suffice for all shown, and as represented each stand consists of an upright flat plate a, having a flanged base b, which is of such a proportionate length and width as to afford a 60 proper support for the material it is to sustain. Any desired height is given to the bracket-stands A, and at or near the upper edge of the same on each side projecting tongues c are formed, which are sharpened toward 65 their free edges. Any desired number of the tongue formations are produced on the upright portions a of the bracket-stands, preferably opposite each other in pairs, and at a proper distance from these tongues a 70 slot d is formed in the upright a of each bracket-stand for the insertion of a sill B, that is preferably made of metal in the shape of an elongated flat bar, which will loosely fit the transverse slot of each bracket-stand, 75 which slots are parallel with the lower surface of the bases b. It is equally feasible to extend the sills B across the sidewalk or longitudinally of the same. For illustration the first-named position will be assumed, as 80 represented in Figs. 1 and 2, so that the pieces of wooden plank C, that are preferably used as treads for the sidewalk, will extend lengthwise of the walk, the length of the similar bars or sills B representing the width of said 85 sidewalk, which, it is apparent, may be increased or diminished as may be required to suit the situation.

In constructing the sidewalk the surface of the ground is rendered level, and, if necessary for stability of the structure, flat stones or brick can be embedded in the ground to form a firm foundation for the bracket-stands A. A number of the sills B, similarly formed, are furnished for the support of the planks C, 95 which are placed upon said sills, that are evenly spaced apart at a proper distance, so as to afford a support for the tread-pieces named.

The parts of the sidewalk are assembled as 100

follows: A sufficient number of the wooden or fire-hardened earthenware tread-pieces C are laid in position upon the sills B, so disposed that a row of bracket-stands A will be located between and engage the edges of the planks oppositely, as shown in Fig. 2. These stands are then clamped toward each other, so as to embed the tongue c in corresponding notches formed in the tread-pieces 10 by providing an abutment-block D for each sill, which blocks are secured upon the outer end portions of the sills by bolts e or other means. At the opposite end of each sill B a clamping-block E is located. Said blocks, 15 which are of similar form, in contour correspond with the shape of the upper portion of the bracket-stands A, and are each slotted transversely near the lower end, producing apertures of a form corresponding to that of the sills and of such relative dimensions thereto that the clamping-blocks when in place may be wedged fast by the introduction in the slots of tapering keys g, as shown in Fig. 2, the action of the clamping-blocks when 20 driven against the upper ends of the bracket-stands serving to draw all intermediate stands and engaged tread-pieces A in close contact and lock them to the sills.

The interposition of the bracket-stands between the adjacent edges of the tread-pieces A produces crevices between said pieces, so that rain or melted snow will not remain on the treads, but will escape between them, and, as there are elongated apertures h formed in the sills B, these pieces are thereby lightened in weight and adapted to permit air to have access to the major portion of the tread-pieces imposed on them.

When the sidewalk is constructed to extend the tread-pieces A longitudinally and their supporting devices across the walk, as is represented in Figs. 1 and 2, the ends of aligning plank or terra-cotta slabs should rest upon a sill, as shown in dotted lines in Fig. 1, and 40 may break joints, which will render the surface smooth and prevent the plank ends from sagging or twisting, the free access of air to the wooden plank on the sides and edges aiding the retention of the material in an unwarped condition. Should the sidewalk be arranged to extend the sills B longitudinally instead of transversely, these sills must then

be joined together at their ends, as shown in Fig. 5, a splice-bar B' being placed below the joint and secured to the sills by bolts, so that 55 an indefinite length of continuous sills may thus be provided and the plank or terra-cotta slabs secured transversely thereon in an obvious manner.

At desired points the abutment-blocks D 60 may be provided with rings m for the hitching of horses, which rings may be formed with the blocks or be secured thereto by a threaded engagement, as shown in Fig. 2.

Having thus described our invention, what 65 we claim as new, and desire to secure by Letters Patent, is—

1. A sidewalk composed of similar bracket-stands, each similarly apertured sidewise and provided with enlarged bases and lateral 70 tongues on opposite sides above the apertures, elongated sills which slide in the apertures of the bracket-stands, tread-pieces having parallel edges which are located intermediately of the bracket-stands on the sills and adapted 75 to interlock with the tongues on the bracket-stands, an abutment-block on one end of each sill, and clamping-blocks which hold the tread-pieces and bracket-stands clamped against the abutment-blocks, substantially as set 80 forth.

2. In a sidewalk, the combination, with a series of similar bracket-stands laterally apertured to receive flat elongated sills and a series of elongated and perforated sills, of a 85 series of tread-pieces located on the sills between the bracket-stands and interlocked with tongues that oppositely project from the sides of the bracket-stands, an abutment-block secured on one end of each sill, sliding clamping-blocks on the opposite ends of said sills, and tapering keys that are adapted to bind the clamping-blocks on the sills, substantially 90 as set forth.
